UNITED STATES PATENT OFFICE.

HANS NORDSTRÖM, OF PETROGRAD, RUSSIA.

INTERNAL-COMBUSTION ENGINE.

1,211,746.

Specification of Letters Patent.

Patented Jan. 9, 1917.

Application filed February 16, 1912. Serial No. 878,092.

To all whom it may concern:

Be it known that I, HANS NORDSTRÖM, a citizen of the Swedish Kingdom, residing at Petrograd, Russia, have invented certain

5 new and useful Improvements in Internal-Combustion Engines; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 In two cycle internal combustion engines working on the principle of uniform pressure, it is difficult to obtain a good combustion at different speeds of rotation. The reason is that these engines, in order to 20 work with advantage, must compress the air provided for the combustion up to a certain extent. The pressure in the cylinder at the beginning of the compression, and, accordingly, the clearing air, must not sink below 25 a certain pressure. If now the clearing out process takes place well at a certain speed of rotation, and the engine is then reduced to half speed, for example, the valves for admitting the clearing air and exhaust gases 30 will remain open for double the time, so that much more clearing air is blown through than is necessary, and the pressure is reduced accordingly. The consequence is that in this 35 case the starting pressure, and, accordingly, the final pressure after compression, will become less. A lesser quantity of air for the combustion and a lower compression are therefore obtained and the result is bad combustion. A useless waste of clearing air also 40 occurs in the following case: If a multiple cylinder engine is running without a load, for example, if a marine engine is running at low speed, it is of advantage to cut off the supply of the combustible to one or more 45 cylinders. The remaining cylinders then receive a good supply of the combustible and work well. Because, however, the clearing out process continues in connection with 50 the idly working cylinders a considerable loss of air takes place.

The present regulating device renders it possible to obtain the best combustion in the cylinder at various speeds of rotation and prevents an unnecessarily large quantity of clearing air being blown through at low speeds of rotation. If, therefore, a clearing

air pump of sufficient size is used, a correspondingly high starting pressure can be obtained in the cylinder, and the efficiency of the engine will be increased. Further, 60 the device enables the supply of clearing air to be simultaneously cut off when putting one or more cylinders out of action. For this purpose an arrangement is chosen which will enable the length of the "open" period 65 to be altered, and this is best done by the valve in question being opened later at lower speed, so that only the quantity of air required for clearing out the cylinder is blown through. In order to obtain an easy adjustment, the air inlet valve can be divided 70 into two separate valves, which are separately actuated, one of which valves serves to shut off the inside of the cylinder, and is, accordingly, opened for a constant period 75 suitable for the highest speed of rotation, while the other valve is an auxiliary valve, is arranged outside, and can be manually adjusted for different periods.

The space between the main valve and 80 the auxiliary valve can be used as a receiver. In this case the clearing out operation is performed by first opening the main valve, whereupon the air contained in the receiver will carry out the first clearing operation. 85 Thereafter, the auxiliary valve is opened and causes, toward the end of the clearing period, air to pass into the cylinder at the desired pressure. The auxiliary valve can remain open after the exhaust channels have 90 been closed, the air last introduced thus serving to refill the cylinder.

On the drawing the invention is illustrated by way of example: Figure 1 being 95 a section of the valve gearing in the working position, Fig. 2, a similar section showing the position of the valve gearing in the case of a cylinder, which has been put out of operation, Fig. 3, a horizontal section through the auxiliary valve, and Fig. 4, a 100 crank diagram.

The combustible is fed into the cylinder through the valve *a*, while the air enters through the main valve *b* and auxiliary valve *c*.

105 *d*, *d'* are slots in the wall of the cylinder which are opened and closed by the piston and serve for the exhaust. The movement of the valves is obtained by the spindle *e*. For the purpose of opening and closing the 110 supply valve *a* a cam disk *f* is provided on the spindle *e*, which disk actuates the valve

through the agency of a roller g mounted on one arm of a bell crank lever h to the other arm of which a rod is attached and said rod is connected to a second bell crank lever, which engages with the valve spindle. The main air valve b is operated by the lever i , which carries a roller k bearing against a cam disk l . The levers h and i turn about an eccentrically journaled spindle m with which the hand lever n is connected. If this lever is in the position I (Fig. 1), the rollers g and k are operated by the cam disks f and l , and the valves are accordingly opened and closed. If, however, the lever is brought into the position II (Fig. 2), the rollers will be moved into the position shown in Fig. 2, in which position they do not come into contact with the cam disks, so that the valves remain closed.

The auxiliary valve consists of a cylindrical casing c , in which a cylindrical valve sleeve o tightly fits said sleeve being adapted to be turned by the hand lever p . In the valve sleeve o is provided a disk r , which is adapted to be moved by a lever s , eccentric rod t , and the eccentric u mounted on the spindle e . By moving the lever p , and the valve sleeve o , connected with said lever, it is now possible to cause said valve to open sooner or later. As in the construction of the auxiliary valve shown in the drawing the disk r works without adjustment, said valve, on raising the lever p , is opened sooner, and, on depressing said lever, later. Fig. 1 shows the piston at the bottom dead point, at which point the pressure has fallen, and the valve b is open and the compressed air contained in the passages between the valves b and r has been admitted to the cylinder through valve b to effect the clearing. No air, however, has yet passed out of the receiver v , because the auxiliary valve c is still closed and is only now opened by the disk r , valve b remaining open and compressed air is admitted to the cylinder at the end of the clearing period.

According to the diagram shown in Fig. 4, in which x represents the top dead point, and y , the bottom dead point, the valve a for supplying the combustible opens at the point a' and closes at a'' , whereupon the expansion of the combustible gases takes place up to the point d' , where the exhaust slots are opened, and the pressure in the cylinder can fall. At b' the valve b is opened and the exhaust gases are blown out up to the point d'' , where the piston again closes the exhaust slots. From d'' up to b'' , where the clearing air valve is closed, the air continues to enter.

With the assistance of the valve c it is rendered possible to begin the clearing out either at b'' , or to delay it, so that it begins at c' . In this case the equalization of the pressure takes place from d' up to c' , the

clearing out from c' up to d'' , and the subsequent entrance of air from d'' up to b'' . The clearing air valve can also be closed at d'' , but it is generally preferable to close this valve somewhat later, because from d'' up to b'' the air can enter into the cylinder and increase the pressure up to that in the receiver v .

The valve c can be so arranged that the air can be entirely cut off by the hand lever p (Fig. 2). Further, this valve may be combined with the regulating device for the supply of the combustible, so that the supply of the combustible and air is simultaneously regulated and cut off. Another way of cutting off the combustible and clearing air consists in moving the lever n into the position II, by doing which the valves a and b are put out of action.

The described arrangement can, of course, also be used where the supply of clearing air is governed by slots in the cylinder.

What I claim and desire to secure by Letters Patent of the United States is:

1. In a two-stroke cycle gas engine, the combination with an air inlet valve, means to supply air to said valve, an auxiliary valve to control the admission of air to said means, means for opening the auxiliary valve, and means operating in conjunction with the latter to advance or retard the opening of said auxiliary valve.

2. In a two-stroke cycle gas engine, the combination with an air inlet valve, means to supply air to said valve, an auxiliary valve to control the admission of air to said means, means for opening the auxiliary valve, and manually operated means operating in conjunction with said auxiliary valve to advance or retard the opening of the latter.

3. A two-stroke cycle gas engine having an air inlet valve, means to supply air to said valve, means operable at each cycle of movement to control admission of air to the air supply means, and means to vary the duration of the passage of the air through said air supply means.

4. In an engine, an air inlet valve, a valve controlling the supply of compressed air to said inlet valve, and a chamber between the valves, and means to open the inlet valve in advance of said second valve and to hold said inlet valve open during the opening of said second valve.

5. In an engine, an air inlet valve, a valve controlling the supply of compressed air to said inlet valve, a chamber between the valves, means operated by the engine to open the inlet valve at a definite point in relation to the piston stroke, means operated by the engine to open the said second valve after the opening of the inlet valve, and means to regulate the extent of opening of the second valve.

6. In a two-stroke cycle engine, an air inlet valve, a compressed air supply valve, a chamber between the valves, means operated by the engine to open the inlet valve to admit clearing air from said chamber, means operated by the engine to operate said supply valve at the end of the clearing period, and means to regulate during the operation of the engine the quantity of compressed air delivered by the latter valve.
7. In a two-stroke cycle engine, an air inlet valve, a compressed air supply valve, a chamber between the valves, means operated by the engine to open the inlet valve to admit clearing air from said chamber, means operated by the engine to operate said supply valve at the end of the clearing period, and hand-operated means to regulate, during the operation of the engine, the quantity of compressed air delivered by the latter valve.
8. In a two-stroke cycle engine, an air inlet valve, means operated by the engine to actuate said valve, an auxiliary valve comprising a casing, a cylindrical valve sleeve therein having opposite ports, a hand lever for rotating said sleeve in said casing and a valve in the sleeve; means operated by the engine to actuate the last mentioned valve and open the same after the air inlet valve at the end of the expelling stroke of
- the piston of the engine, and a chamber between the air inlet valve and auxiliary valve.
9. In a two cycle engine, an air inlet valve, means operated by the engine to actuate said valve, an auxiliary valve to control the supply of compressed air to said inlet valve, a chamber between the valves, means to regulate the quantity of air passing through the auxiliary valve and means to place the air inlet valve out of operation, and thereby render the auxiliary valve ineffective.
10. In a two-cycle engine, an inlet valve for combustible, an air inlet valve, an auxiliary valve, a chamber between the two last mentioned valves, mechanism operated by the engine to open the air inlet valve in advance of the auxiliary valve, mechanism operated by the engine to simultaneously actuate the valve for combustible and the auxiliary valve, and means to control the time of opening of the auxiliary valve independently of the other two valves.

In testimony that I claim the foregoing as my invention, I have signed my name in presence of two subscribing witnesses.

HANS NORDSTRÖM.
